MANTLE MOUNTING

Carl Bramming, Nashville, Tenn., assignor to Aladdin Industries, Incorporated, Nashville, Tenn., a corporation of Illinois

Application June 11, 1953, Serial No. 361,025

6 Claims. (Cl. 67—38)

This invention relates to hydrocarbon illuminating devices and more specifically to lamps employing a mantle which is heated by a controlled flame to incandescence to provide light.

One of the continuing problems faced by manufacturers of mantle lamps is the provision of a mantle mounting device which will perform the function of centering the incandescent mantle without distorting or corroding at an uneconomical rate. The mantle mounting must additionally be inexpensive and easy to manufacture.

It has been found advisable to provide a mantle mounting with each new mantle purchased so that when the mantle is renewed periodically the mantle mounting ring is also renewed. This makes it possible to form the mantle mounting ring of thinner, cheaper material, such as sheet steel, which is not as resistant to corrosion and erosion as is a material such as brass, but which, in the light weight in which it is used, is very resistant to heat transfer from the adjacent flame to the burner basket.

Moreover, it is desirable to reduce the amount of heat transfer from the mantle mounting to components of the burner, which is accomplished in accordance with the present invention by eliminating one-half of the flange which normally rests on the burner cone and by bending the parts thus eliminated downwardly to constitute complementary portions of the baffle which control the flow of outer air to the wick. In this manner the edges of the partial flanges may be utilized as locking components which engage lugs on the burner cone or on a burner basket and the downwardly bent skirt portions become useful adjuncts in the centering of the mounting.

Another vital advantage of the new mounting with the depending flange or skirt portions which make contact with portions of the baffle is that of keeping the burner cone and the baffle aligned. Owing to the high heat, the burner cone or the baffle frequently warps so that one is not in proper alignment with respect to the other. That results in inefficiency of the burner. The new mantle mounting which is in engagement with both, the burner cone and the baffle, is capable, in addition to its other valuable functions, of acting as a brace between cone and baffle, thereby preventing warping. If warping does take place, a new mounting can be effective in realigning the warped parts.

Accordingly, it is an object of the invention to provide a mantle mounting which complements parts of a hydrocarbon burner of the wick type in a manner to reduce the amount of material used while simultaneously reducing the heat conduction from the mounting to the burner and to utilize the structural advantages obtained by cutting down the material to provide a locking means to secure the mounting on the cone and a centering means which also complements the baffle controlling the air flow.

A further object is to provide a mantle mounting ring designed for cooperative engagement in a burner cone in such a manner as to permit the mantle mounting to complete a portion of the structure of the burner cone.

2

A further object is to provide a mantle mounting which may be employed on older forms of burner heads and galleries as well as the newer more simplified types.

Further objects and advantages of this invention will be apparent from the consideration of the following specification in connection with the accompanying drawings, in which:

Fig. 1 is a view in perspective of the mantle mounting ring and harp,

Fig. 2 is a plan view of the mantle mounting ring,

Fig. 3 is a view in section on the line 3—3 of Fig. 2 with the mantle mounting ring positioned on a new type burner cone,

Fig. 4 is a view in section on line 4—4 of Fig. 2 with the mantle mounting ring positioned on a burner cone of the older type,

Fig. 5 is a plan view of the burner cone of Fig. 3, and Fig. 6 is a plan view of the burner cone of Fig. 4.

The mantle mounting plate 10 has an annular downwardly opening cup portion near its center formed with a flat base 11 and a substantially vertical annular wall 12. Inwardly from the base portion 11 the substantially vertical wall 13 terminates in a horizontal flange 14 the size of which partly determines the volume of air which is introduced to the inside of the mantle. It will be appreciated that the cup formed by the walls 12 and 13 and the base 11 is annular and that in operation the mantle, not shown, nests around the outside of the wall 12.

Formed outside of the wall 12 is a pair of arcuate channel portions having a base 15 and an outside arcuate wall 16. These arcuate channel portions or wells embrace the outside of the mantle in the operative position.

The wall 16 extends upwardly into a horizontal portion 17 and a further vertical portion 18 which supports the ear 19. The diametrically opposite ears 19 support vertical walls 20 in which are formed the partial sleeves 21, each of which embraces one of the arms 22 of the harp 23. The upper horizontal arm of the harp 23 includes the crank yoke 24, from the center of which the mantle is hung in operative position so that its lower edge extends adjacent the portion 15 of the mantle mounting base plate and between the end walls 12 and 16.

In the angular intervals between the upturned walls 16, the mantle mounting base 10 is formed downwardly at a point slightly below the channel bottom 15 to form a pair of diametrically opposite downturned or depending flanges 25, each extending for an angular distance in excess of 90°. As will appear later, these downwardly extending flanges 25 cooperate functionally with the structure of the new burner cone, as shown in Fig. 3, and, in case of installation with the older type burner cone, as shown in Fig. 4, the flanges 25 nest around the burner baffle without interfering with the operation of the burner.

In Fig. 3, the new mantle mounting is shown in operative position on a newer type simplified burner cone. In that structure the burner 26 is shown as being formed with a baffle 27 having a plurality of apertures 28 through which air is supplied to the wick. The baffle 27 supports the inner frusto-conical portion 29 the function of which is to channel the air in such a manner as to most efficiently direct it against the wick, thereby providing complete combustion and, therefore, a blue flame.

The upper burner cone 30 is formed with an inner aperture at 31 and a pair of downwardly diametrically opposite extending inner flanges 32, extending from the upper surface 33 of the cone 30.

In the assembled condition, the mantle mounting 10 is positioned so that the lower annular surface 15 is supported by the upper annular surface 33 of the burner cone 30. The flanges 25 are initially placed inside the aperture 31 adjacent the downwardly extending flanges 32 and resting on the horizontal flange 34. Because the

aperture 31 is not circular, and because the top 33 extends radially inwardly in places other than where the flanges 32 are situated, the mantle mounting 10 is locked into position by being rotated relative to the burner cone 30. The shoulder 35 fits under the top 33 thereby locking the mantle mounting plate 10 into position.

It will be appreciated that the downwardly extending flanges 25 bridge or cover the angular gaps between the flanges 32 and hence complement the flanges 32 in completing the air passage to the inside of the mantle.

As shown in Fig. 4, the mantle mounting 10 may also be assembled with the older type gallery. There the lower baffle 36 and the upper baffle 37 are supported in spaced relationship to the perforated burner cone 38. The upper surface 39 of the burner cone 38 is an annulus which slopes inwardly towards a short vertical wall 40 which terminates in a horizontal flange 41 which in turn defines the upper aperture 42. In position, the partial annular wall 16 of the mantle mounting base 10 fits inside the flange 41 in the aperture 42, the horizontal wall 17 being supported on the flange 41. The wall 12 fits, on its inside edge, the upper portion of the baffle 37. The downwardly extending flange 25 is displaced radially sufficiently so that it nests around the wide portion 43 of the baffle 37. The mantle in its operative position will lie between the wall 12 and the wall 16 for almost half of the circumference of the mantle mounting base 10 and between the wall 12 and the flange 41 in slightly more than half of the circumference of the mantle mounting 10.

Having described my invention, what I claim as new and desire to protect by Letters Patent is:

1. A mounting for a mantle for an incandescent lamp comprising an upstanding annular wall adapted to be received within a mantle, a pair of upstanding arcuate walls of greater radius than said inner wall and connected thereto for partially embracing the outside of a mantle, a pair of ears positioned outwardly from the arcuate walls, a harp supported on said ears and adapted to support a mantle, and a pair of downwardly turned depending flanges formed on said inner wall in the angular intervals between said annular walls and adapted to meet with complementary downwardly extending flanges in a burner cone to form an air passage.

2. In a mantle mounting in which a mantle-supporting harp is mounted on a pair of sidewardly extending ears, the provision of mantle-positioning and air-directing means comprising an upstanding annular inner wall, a pair of upstanding arcuate outer walls, the arcuate walls and the inner wall being connected by a pair of bottom walls and together defining a pair of mantle-receiving channels, and a pair of downwardly extending flanges positioned between said pair of arcuate outer walls and supported from said inner wall, said pair of flanges being adapted to meet with downwardly extending complementary flanges in a burner cone to form an air passage.

3. In a mantle mounting in which a mantle-supporting harp is mounted in a pair of partial sleeve members formed on a pair of sidewardly extending ears, the provision of mantle-positioning and air directing means comprising an annular inner wall, a pair of arcuate outer walls, a pair of arcuate channel bottom elements connecting together said outer and inner walls and together defining a pair of mantle-receiving channels, a pair of arcuate retainer shoulders formed between said pair of arcuate outer walls and below the level of said annular channel bottom elements, and a pair of downwardly extending flanges depending from said pair of arcuate retainer shoulders, said pair of flanges being adapted to meet with downwardly extending complementary flanges in a burner cone to form an air passage.

4. In a burner for a mantle lamp, the combination comprising an outer burner cone having an inwardly projecting generally radial-annular flange, a pair of downturned diametrically opposite arcuate flanges depending

from said inwardly projecting flange with angular openings therebetween, a mantle mounting ring for supporting a mantle on said cone, said mantle mounting ring including a generally upstanding annular inner wall for receiving the lower edge of the mantle therearound, a pair of diametrically opposite upstanding arcuate wall elements spaced outwardly from said inner wall, a mantle supporting harp mounted on said arcuate wall elements, bottom wall elements connecting the lower edges of said arcuate elements with the lower edge of said inner wall to define arcuate channels for receiving the lower edge of the mantle, said bottom wall elements being engageable with the upper side of said inwardly projecting flange of said cone, a pair of diametrically opposite shoulder elements extending outwardly from said inner wall between said bottom wall elements and below the level thereof for movement under said inwardly projecting flange to lock said mantle mounting ring to said cone, and a pair of downturned flanges depending from said shoulder elements for engagement with the inner sides of said downturned flanges on said cone to bridge said angular openings therebetween and thereby define therewith a complete annular baffle flange.

5. A mantle mounting for use with a mantle lamp burner cone having an inwardly projecting generally radial flange formed with a pair of downturned diametrically opposite arcuate flanges with angular openings therebetween, said mantle mounting comprising, in combination, an upstanding annular inner wall for receiving the lower edge of a mantle therearound, a pair of diametrically opposite upstanding arcuate wall elements spaced outwardly from said inner wall, a mantle supporting harp mounted on said arcuate wall elements, bottom wall elements connecting the lower edges of said arcuate elements with the lower edge of said inner wall to define arcuate channels for receiving the lower edge of the mantle, said bottom wall elements being engageable with the upper side of the inwardly projecting flange on the cone, a pair of diametrically opposite shoulder elements extending outwardly from said inner wall between said bottom wall elements and below the level thereof for movement under the inwardly projecting flange to lock the mantle mounting to the cone, and a pair of downturned flanges depending from said shoulder elements for engagement with the inner sides of the downturned flanges on the cone to bridge the angular openings therebetween and thereby define therewith a complete annular baffle flange.

6. A dual purpose mantle mounting for use either on a first burner having an outer cone formed with an inwardly projecting generally radial flange with a pair of downturned diametrically opposite arcuate flanges and angular openings therebetween or with a second burner provided with an annular baffle and an outer cone with an inwardly projecting flange element generally opposite from the upper end of the baffle, said mantle mounting comprising, in combination, an upstanding annular inner wall for receiving the lower edge of a mantle therearound, a pair of diametrically opposite upstanding arcuate wall elements spaced outwardly from said inner wall, a mantle supporting harp mounted on said arcuate wall elements, bottom wall elements connecting the lower edges of said arcuate elements with the lower edge of said inner wall to define arcuate channels for supporting the lower edge of the mantle, said bottom wall elements being engageable with the upper side of said inwardly projecting flange on the first burner, said bottom wall elements being adapted to be inserted between the baffle and the inwardly projecting flange element on the second burner with said inner wall and said arcuate elements engaging the baffle and the flange elements, a pair of diametrically opposite shoulder elements extending outwardly from said inner wall between said bottom wall elements and below the level thereof, said shoulder elements being adapted to be moved under

the inwardly projecting flange of the first burner between the downturned flanges to lock the mantle mounting to the first burner, and a pair of downturned flanges depending from said shoulder elements for engagement with the inner sides of the downturned flanges on the first burner to bridge the angular openings therebetween and thereby define therewith a complete annular baffle flange, said downturned flanges on said mantle mounting being adapted to be telescoped over the annular baffle on the second burner to maintain the baffle in 10 centered relation to the flange element on the second burner.
